COIN CHUTE

Bernhard C. Grunig, Chicago, Ill.

Application July 29, 1937, Serial No. 156,305

6 Claims. (Cl. 194—102)

This invention pertains to a coin chute and to fraud prevention means effective to prevent the operation of the slide by deposit therein of two or more tokens, the aggregate thickness of which is substantially equal to the thickness of a proper coin.

More specifically stated, it is an object of the invention to provide a coin chute of the type having a mounting plate on which is formed a lateral sleeve for the reception of a coin slide having a coin aperture therein, the bottom of the sleeve or guide providing a bottom for the coin aperture to permit transposition of a coin in the coin pocket from one side of the mounting plate 10 to the other by movement of the slide, there being a discharge opening in the sleeve or guide portion with which the coin pocket or aperture registers when the slide reaches a predetermined position, thus permitting the coin to gravitate 20 out of the coin aperture in the slide through the discharge opening in the frame.

A further object is the provision in a coin chute structure of the type just characterized in which body portions of the slide on the peripheral edge 25 of the coin pocket therein are punched or extruded or crimped in a manner to provide projections into the coin aperture and which are adapted to permit a coin of predetermined thickness to rest in the pocket for free transport by 30 the slide toward the discharge opening, and which are effective to raise the edge of the coin resting in the aperture a distance sufficient to permit the proper coin to be transported as aforesaid; but when two thin tokens or shims are 35 placed in the aperture, the arrangement is such that the edge of the uppermost token will project and bear against an abutment to prevent movement of the slide.

Yet another object is the provision in a coin 40 chute of the class described of a thin coin slide having a substantially circular aperture cut therethrough and providing a coin pocket, said slide having marginal edge portions deformed to provide an inward projection dimensioned to 45 permit a coin of predetermined thickness to rest in the pocket substantially within the plane of the slide for free transport by the latter, the edge of the coin in the pocket, nevertheless, being tilted an amount adequate to cause the edge 50 of a second coin or token placed upon the first to extend beyond the plane of the slide to bear against the chute structure in a manner to prevent operation of the slide.

Other novel aspects of the invention reside in 55 particular features of construction and operation

of the embodiment hereinafter to be described and claimed.

In the drawing:

Fig. 1 is a top plan view of the improved coin chute;

Fig. 2 is a vertical section along lines 2—2 of Fig. 1;

Fig. 3 is an enlarged fragmentary vertical section illustrating the operation of one form of the fraud preventive means;

Fig. 4 is a section similar to Fig. 3, but showing the operation of a modified form of slide;

Fig. 5 is a bottom perspective view of the form of slide shown in Fig. 4; while

Fig. 6 is a vertical sectional view similar to Fig. 2 but showing the slide operated by a pair of shims, there being no fraud preventive means.

One form of a coin chute illustrative of the invention is shown in Fig. 1 and includes a frame constituting a guide and comprising a vertical 20 mounting plate 10 having a transverse sleeve portion including front and back sections 11 and 12. A slide 13 of substantially planar form is seated in the sleeve portion and is reciprocable 25 therein for the purpose of positioning a coin 25 pocket 14 therein on either side of the mounting plate 10 to transport a coin from the front section 11 to the back section 12.

As seen in Fig. 1, the slide 13 is in its normal coin depositing position, and the front sleeve section 11 is cut away as at 15 to expose the pocket 14, the opposite inner surface of the entire sleeve formation constituting a bottom for the coin pocket 14 so that when a coin is deposited in the latter and the slide moved, the coin will be 35 transported and will glide over said bottom portion.

As seen in Fig. 2, there is provided a drop-out opening 16 in the front sleeve section 11 in a position for registration with the coin pocket 40 14 in the slide when the latter is in its normal coin receiving position. The diameter of the drop-out opening 16 is slightly smaller than that of the coin pocket, so that a token or coin of less than a predetermined and necessary diameter to 45 fit in the pocket 14, will drop through the opening 16.

The rearward sleeve section 12 has a substantially solid upper surface 17 upon which is mounted a dog 18 by means of a pin 19 extending 50 into an integral boss 20; a coil spring is pivotally mounted between its ends on the pin 19 and has a bent free end portion 21 engageable with the dog 18 and an opposite end portion 22 bearing 55 against the surface 17 of the rear section. There

is provided an elongated slot 23 through which the nose portion of the dog 18 may pass under urging of the spring 21, and on the opposite or bottom surface of the rear section 12 there is 5 provided an irregularly shaped opening 24 (see also Fig. 2) into which the nose of the dog 18 may pass under certain conditions.

Spaced rearwardly (to the right) of the irregular drop-out opening 24 on the bottom surface of 10 section 12, is a discharge opening 25. The right-hand portion of the upper wall or surface 17 of the inner sleeve portion 12 is cut away as at 26 to expose a portion of the discharge opening 25, there being, however, an edge portion 27 of the 15 section 17 overlying the discharge opening 25 for purposes which will hereinafter appear. Mounted by suitable means such as the washer 28 and screw 29, threaded into the frame section 12, is a horseshoe magnet 30 having its poles 31 con- 20 fronting the rearward edge 27 of the sleeve portion 17 and substantially overlying the discharge opening 25 so as to attract a paramagnetic coin element therein and prevent the same from falling through the discharge opening.

Communicating between the front and rear sections 11 and 12 through the mounting plate 10 is a small channel 32 in which rides a depending boss 33 stamped into the slide 13, and this channel 32 continues into both of the drop-out 25 openings 16 and 24 (Fig. 2).

Mounted on the rearward side of the vertical mounting plate 10 between opposite vertically extensive mounting bosses 34 is a combination slide stop and reject apron having an inclined portion 35 for the purpose of directing rejected tokens passing through the rear discharge opening 24, the apron also having a vertical portion 36 which fits flush against the inner surface of the mounting plate 10 and which is provided with 30 an upwardly extending ear or lug 37 which projects into the channel 32 and provides an abutment against which the depending ear 33 on slide 13 may bear to limit the outward movement of the slide.

It will be observed in Fig. 2 that when the slide is in the normal position there shown, the nose of the dog 18 rests upon the rearward upper surface portion of slide 13 adjacent the stopping lug 33, the dog being in raised position 45 against the tension of the spring 21. There is provided in the slide 13 an elongated slot 38 extending radially away from the edge of the coin pocket 14 opposite the dog 18.

Thus, when a token such as a washer having 50 a central opening is deposited in the pocket 14 and the slide is pushed in, spring 21 will urge the nose of the dog into the perforate portion of the token or washer and prevent further rearward movement of the slide. Should the coin or token be a proper one, that is not perforate, the slide may be moved inwardly its full stroke and when the left-hand edge of the coin in pocket 14 has passed the nose of dog 18, the latter will be urged by its spring 21 into the elongated slot 38, 55 thus permitting full stroke movement of the slide so that the coin in pocket 14 will be positioned over the discharge opening 25 and gravitate through the latter to operate some desired instrumentality.

There is a method by which slides of this type 60 may be defrauded and which includes the deposit of two tokens or wafers, the aggregate thickness of which is substantially equal to the thickness of a proper coin, one of these tokens 65 or shims being sufficient to operate the instru-

mentality if it can be passed through the discharge opening 25. In practice these shims are frequently of paramagnetic material, and the object of using them is to permit the topmost one to be attracted by the magnet 30 and held by the 5 same while the lowermost token discharges through the opening 25 due to the fact that the magnetic flux at the poles of the magnet is inadequate to hold the same, since the magnetic circuit is substantially completed by the top- 10 most token or shim.

In order to prevent such fraudulent operation, the present invention provides means for tilting a coin of predetermined and proper size in the 15 pocket 14 without causing the edge of the coin to project beyond the plane of the slide itself, thus assuring that the slide may be freely moved and that the tilted coin will freely pass into the 20 guide sleeve beneath the vertical mounting plate 10.

The aforesaid means in the embodiment shown includes a pair of spaced inwardly projecting crimps or fingers 40 extending radially inward from the edge of the pocket 14 and preferably spaced on either side of the longitudinal center line through the pocket 14. These fingers or projections 40 may be provided by a number of methods, one of the simplest being that of crimping or stamping or pinching body portions of the slide at the edge of the pocket 14 so as to 25 cause the extrusion of some of the material in the manner set forth.

It is further desirable to form the fingers 40 with an angular surface 41 (Fig. 3), the inclination being from the edge of the pocket 14 downwardly toward the center of the pocket, the average inclination being adequate to tilt a proper coin of predetermined thickness so that the right-hand edge portion thereof will be positioned close to the upper planar surface of the 30 slide 13 without, however, projecting beyond this surface.

In Fig. 3 there are shown in dotted lines two shims or fraudulent tokens 42 and 43 in position in the pocket 14, and it will be observed that the right-hand upper edge 42' of the uppermost coin projects beyond the upper face of the slide 13 a distance such that when the slide 13 is moved inwardly this edge portion 42' will abut against an edge 45 of the vertical mounting plate 10 and arrest the movement of the slide by virtue of the bearing engagement of the left-hand edge of the topmost coin 42 with the left-hand inner surface portions of the pocket 14. In this manner any transportation of the shims beyond the vertical mounting plate 10 is entirely defeated.

Fig. 6 illustrates what would happen if the shims 42 and 43 of Fig. 3 were employed without the safeguard of the fraud preventive fingers or formations 41. In such a case, the two shims would be carried to the rear section 12 and the topmost shim 42 would be attracted and be held by the magnet 30 while the lowermost shim 43 would fall through the discharge opening 25 and fraudulently actuate the controlled instrumentality, the field of the magnet being bridged by the top token 42 and being inadequate to hold the bottom token or being sufficiently weakened so that jarring will cause the lower shim to be 70 dislodged.

A modified form of the fraud preventive means is disclosed in Fig. 5 wherein the inwardly projecting formations or fingers are situated on an opposite side of the coin pocket 14' and are 75

provided by a pair of spaced punches 46 disposed on either side of the elongated dog channel 38. These punches 46, it will be observed, are made from the bottom surface of the slide 5 13 and are calculated to provide an angularly extending boss similar to the fingers 41 of Fig. 3 insofar as they serve to tilt a coin in the pocket, in the same general manner as described in conjunction with Fig. 3. In this instance, however, 10 the tilt is opposite to that of the structure of Fig. 3, with the result that when two shims are in the pocket 14, inward movement of the slide will be prevented by the wedging action of the raised edge (now the left-hand upper edge instead of the right-hand edge as in the case of Fig. 3) of the topmost shim with the portion 45 of the guide or mounting plate 10.

It will thus be apparent that the invention provides a very simple structure which is nevertheless highly efficient for its intended purpose, and 20 it will further be apparent that the fraud preventive means in the form of the tilting fingers 46, as applied to the coin receiving pocket, may be applied to any coin slide of the planar type 25 wherein a coin is normally disposed within the plane of the slide for movement in a guide member, the fingers being effective to tilt an unauthorized coin or combination of coins or shims, so as to project the edge portion thereof out of 30 the pocket and beyond the plane of the slide for abutment with some portion of the guide to prevent further movement of the slide. Moreover, it will be apparent that various changes in 35 form and location may be made in the particular construction described for purpose of illustration, and it is my intention that all equivalent constructions and all modifications and rearrangements of parts or elements shall be included within the call of the appended claims.

Having thus described my invention, what I 40 claim as new and desire to protect by Letters Patent is:

1. A coin chute including a frame providing a sleeve, a substantially flat slide reciprocable in 45 said sleeve and having a coin pocket adapted to hold a proper coin of predetermined thickness for transport in said sleeve by the slide said coin being of lesser thickness than said slide, and said pocket having spaced inwardly tilted projections adapted to tilt said coin therein without preventing movement of said slide in said sleeve, such movement being prevented, however, by engagement of the coin with the frame when the coin or token in said pocket is of a thickness greater 55 than that of said proper coin.

2. A coin chute including a sleeve-like guide, a thin slide reciprocable therein and having a hole therethrough constituting a coin pocket in 60 which a coin may lie substantially in the plane of the slide, an underlying surface of said guide providing a bottom for said pocket and over

which a coin therein moves when said slide is moved, said hole having means on the edge thereof for tilting a coin therein so as to project an edge portion of a coin of greater than predetermined thickness beyond the plane of the slide 5 for engagement with said guide to block movement of said slide.

3. In a device of the class described, a coin slide of substantially planar form and having a coin pocket in which a coin of predetermined thickness is adapted to lie within the plane of the slide and means projecting inwardly of the pocket to tilt said coin therein without projecting the same beyond the plane of the slide, coin elements of greater than predetermined thickness 10 projecting out of said plane, and means in said device positioned along the path of movement of said slide and coin pocket and engaged by a projecting coin to prevent operative movement 15 of the slide. 20

4. A coin slide of the type adapted to reciprocate in a guide sleeve, said slide having a coin pocket adapted to receive a coin of predetermined thickness and which will lie therein substantially within the plane of the slide, said pocket having 25 a finger formation extending inwardly from an edge thereof and adapted to tilt said coin therein without exposing the same beyond the plane of said slide, but enough to expose an edge portion of a second coin or token placed in said pocket 30 upon the first when the aggregate thickness of the two coins or tokens is greater than said predetermined thickness.

5. A coin slide of substantially planar form and having a coin pocket in which a coin of predetermined thickness is adapted to lie within the plane of the slide, and means projecting inwardly of the pocket and slanted toward the center of the same to tilt said coin therein without projecting the same beyond the surface of said slide 35 to interfere with the movement of the latter. 40

6. In a device of the class described, a stationary member constituting a mounting, a movable member carried on said mounting and operable to transport a coin from one position to another 45 thereon, a pocket in said movable member and adapted to receive and position a proper coin of predetermined thickness so as to lie substantially within the plane of said movable member so as not to obstruct movement of the latter relative to said mounting, and means on said movable member for tilting coin elements in said pocket, coin elements of greater than predetermined thickness being in part projected thereby out of the plane of said slide, and means including a 50 part on said mounting arranged to be engaged by the projected part of a coin element of greater than predetermined thickness to prevent effective movement of said movable member. 55

BERNHARD C. GRUNIG. 60
